UNITED STATES PATENT OFFICE.

FRANK CHATEAUNEUF, OF HAVERHILL, MASSACHUSETTS, ASSIGNOR TO UNITED SHOE MACHINERY COMPANY, OF PATERSON, NEW JERSEY, A CORPORATION OF NEW JERSEY.

SEWING-MACHINE.

1,190,726.

Specification of Letters Patent. Patented July 11, 1916

Application filed November 17, 1911. Serial No. 660,745.

To all whom it may concern:

Be it known that I, FRANK CHATEAUNEUF, a citizen of the United States, residing at Haverhill, in the county of Essex and State of Massachusetts, have invented certain new and useful Improvements in Sewing-Machines; and I do hereby declare the following to be a full, clear, and exact description of the invention, such as will enable others skilled in the art to which it 5 pertains to make and use the same.

This invention relates to curved hook needle sewing machines and more particularly to a looper mechanism for such machines.

As is well known to those skilled in the art, in a sewing machine having a hook or barb needle the thread is delivered to the needle and laid in the barb thereof by a device termed a "looper." The looper is provided with a thread guiding eye through which the thread passes, located in position to coöperate with the needle and the looper is operated to rotate the eye thereof about the needle at the beginning of the formation 10 of each stitch and thereby lay the thread about the same.

The object of the present invention is to produce a curved hook needle sewing machine having a novel and improved looper mechanism for laying the thread in the barb of the needle in which the looper is positively actuated in every direction.

In carrying out the above object the machine is provided with a looper mechanism 35 comprising an oscillatory lever, a looper lever mounted on the first lever to oscillate therewith and also arranged to oscillate independently of the first lever in a plane angular to the plane of oscillation of the first 40 lever and a looper mounted on the looper lever. The said mechanism further comprises means for oscillating both of said levers constructed and arranged to impart positive movements to the looper in every direction. The first lever and the looper lever are preferably arranged so that their 45 planes of oscillation are substantially perpendicular to each other and so that the plane of oscillation of one of the levers is substantially perpendicular to the plane of the needle. By the combined movements of said levers the looper is operated to carry the eye thereof about the needle.

Certain other features of the invention 55 consist of certain novel constructions, arrangements and combinations of parts, here-

inafter described and claimed, the advantages of which will be obvious to one skilled in the art from the following description.

In the drawings illustrating the invention 60 in its preferred form, Figure 1 is a side elevation of a portion of a curved hook needle sewing machine embodying the invention. Fig. 2 is a front elevation of the parts shown in Fig. 1. Fig. 3 is a side elevation of the mechanism shown in Fig. 1 taken from the left hand side of the machine. Fig. 4 is a detail sectional view taken on a line 4—4 of Fig. 1 and Fig. 5 is a detail sectional view taken on the line 5—5 65 of Fig. 2.

The invention as illustrated is applied to a welt and turn shoe sewing machine of the well known Goodyear type, and, as such machines are familiar to those skilled in the 75 art, only so much thereof is shown as is necessary for an understanding of the present invention.

In the machine illustrated in the drawings the looper 1 is provided with a thread guiding eye formed by a thread tube 2 for guiding the thread and is located in position to coöperate with the curved hook needle indicated at 3. In order to permit the looper 80 to oscillate in a direction to bring the looper in front of and to the rear of the path of the needle or in a direction parallel with the plane of the needle, the looper is secured to a looper lever 4, pivoted upon a stud 5, carried by a lever 6 hereinafter described, the 85 said stud being arranged substantially perpendicular to the plane of the needle in one position of the looper. The looper may be formed integral with said looper lever as in the construction illustrated or it may be constructed separate from said lever and secured thereto in any suitable manner.

A slot 7 is formed in the looper lever adjacent the inner end of the lever 6 and a bolt 8 is passed through said slot and is secured in a perforation in the lever 6 to restrain the looper lever 4 from lateral movement with relation to the lever 6 while permitting the looper lever to oscillate on the stud 5. The lever 4 is oscillated on the stud 100 5 to give the desired forward and rearward movements to the looper by means of a slide 9 operating in a guide 10 in the frame and held therein by a cap plate 11. The said slide is connected at its forward extremity 105 with the lever 4 and is reciprocated in said guide by a closed cam formed by a face cam

groove 12 in the cam disk 13, carried by the main shaft 14 of the machine, in which cam groove a cam roll 15 attached to the extremity of the slide is arranged to operate. The slide is connected with the lever 4 by means of a block 16, journaled on a pin 17, clamped in the forward extremity of the slide 9, said block being received in a suitable slot 18 in the lever 4. The slot 18 is formed some-
10 what longer than the block 16 to permit the lever 4 to oscillate about the stud 5 during the reciprocatory movement of the slide 9.

The block 16 is constructed of considerable width for a purpose which will hereinafter appear and on this account projects through the slot 18 beyond the lever 4. The lever 6 is formed with a recess 19 to receive the forward extremity of said block and permit the same to move freely therein during the movements of the slide. Provision is made for varying the path of movement of the lever 4 and thereby of the looper so that the looper may be caused to move in proper relation to the needle by forming the slide 9 in two parts indicated at 20 and 21 and adjustably connecting the parts by means of a bolt 22 passing through a slot 23 in the part 21 and screwed into the part 20. The two parts 20 and 21 are formed 25 with intermeshing teeth upon their engaging faces to prevent the relative displacement of the parts when clamped in adjusted position.

In order that the looper may oscillate in a direction to carry it across the plane of the needle, the lever 6 upon which the looper lever 4 is mounted is pivoted upon a stud 24, preferably arranged parallel with the plane of the needle so that the lever oscillates in a plane perpendicular to the plane of the needle. The rear extremity of the lever 6 extends upwardly over the cam disk 13 and the lever 6 is oscillated upon the stud 24 to impart oscillations to the looper 30 in a plane perpendicular to the plane of the needle by a closed cam formed by a peripheral cam groove 25, the faces of which engage a cam roll 26 attached to the extremity of the lever 6 and operating in said groove. As the lever 6 is oscillated to impart movements to the looper in a plane perpendicular to the plane of the needle, oscillatory movements are imparted to the lever 4 thereby moving the looper forwardly 35 and rearwardly with relation to the path of the needle or in direction parallel with the plane of the needle, the block 16 because of its width engaging in the slot 18 throughout the lateral movements of the lever 4. There is sufficient play between the block 16 and the faces of the slot 18 in the lever 4 to prevent binding of the block in the slot during the oscillatory movements of the lever 6 about its axis.

The thread leading from the source of

supply through the wax pot and tension (not shown) extends over the rolls 27 and 28 of the take-up and from the take-up downwardly through the eye of the looper. The combined oscillations imparted to the 70 looper lever 4 and the lever 6 result in a rotary movement of the looper about the needle.

The mechanism for operating the looper is simple in construction, certain and reliable in operation and inexpensive to manufacture. The movements of the looper are made positive in every direction and the disadvantages incident to the use of the 75 spring actuated mechanisms is avoided.

It frequently happens that the looper is worn by the passing of the thread through the eye thereof to such an extent that it has to be discarded. In the present invention a removable thread tube through which the 85 thread passes is mounted on the looper to form the eye thereof and when this tube becomes worn it may be removed and replaced by another, thereby saving the expense of providing an entire new looper. In the 90 drawing the thread tube indicated at 2 is removably secured in a split clamp 29 formed in the extremity of the looper arm 30 by means of a clamp screw 31.

Having explained the nature and object 95 of the invention and having described one form of mechanism in which it may be embodied, what is claimed is:

1. A sewing machine having, in combination, stitch forming mechanism including 100 a curved hook needle, looper mechanism comprising a lever mounted to oscillate in a single plane substantially perpendicular to the plane of the needle, a looper lever mounted on the forward end of said lever to 105 oscillate in a plane substantially perpendicular to the plane of oscillation of the first lever, a looper carried by the looper lever, positively acting means for oscillating the first lever and positively acting means for 110 oscillating the looper lever in timed relation to the oscillating movement of the first lever to carry the looper about the needle.

2. A sewing machine, having, in combination, stitch forming mechanism including a 115 curved hook needle, looper mechanism comprising a lever mounted to oscillate above the needle in a single plane substantially perpendicular to the plane of the needle, a looper lever pivotally mounted on the forward end of the said lever to oscillate in a 120 plane substantially perpendicular to the plane of oscillation of the first lever, a looper carried thereby, a slide, connections between the slide and the looper lever for 125 oscillating the looper lever, means for actuating the slide, and means for oscillating the first lever.

3. A sewing machine having, in combination, stitch forming mechanism including a 130

curved hook needle, looper mechanism comprising a lever mounted to oscillate above the needle in a plane substantially perpendicular to the plane of the needle, a looper lever pivotally mounted on the forward end of the lever to oscillate in a plane substantially perpendicular to the plane of oscillation of the first lever and projecting below the first lever, a looper carried at the lower end of the looper lever, a slide arranged to reciprocate transversely of the line of feed, connections between the slide and the looper lever for oscillating the looper lever from the slide, means for actuating the slide and means for oscillating the first lever.

4. A sewing machine having, in combination, stitch forming mechanism including a curved hook needle, looper mechanism comprising a lever mounted to oscillate in a plane substantially perpendicular to the plane of the needle, a looper lever mounted on the forward end of said lever to oscillate in a plane substantially perpendicular to the plane of oscillation of the first lever, a looper carried by said looper lever, a slide, connections between the slide and the looper lever for oscillating the looper lever from the slide, said slide having provision for adjustment to vary the path of movement of the looper, means for actuating the slide and means for actuating the first lever.

5. A sewing machine having, in combination, stitch forming mechanism including a curved hook needle, looper mechanism comprising a lever arranged to oscillate in a single plane, a looper lever mounted on said first lever to oscillate therewith and also arranged to oscillate independently of the first lever in a plane substantially perpendicular to the plane of oscillation of the said first lever, a looper carried by said looper lever, positively acting means to oscillate said first lever and positively acting means to oscillate the second lever in timed relation to the oscillatory movements of the first lever to carry the looper about the needle.

6. A sewing machine having, in combination, stitch forming mechanism including a curved hook needle, looper mechanism comprising a lever mounted to oscillate in a single plane, a looper lever arranged to oscillate with the first lever and also to oscillate independently of the first lever in a plane angular to the plane of oscillation of the first lever, a cam roll on the first lever, a closed cam in which said cam roll operates for oscillating the first lever, and mechanism for oscillating the looper lever comprising a cam roll and a closed cam in which said cam roll operates.

7. A sewing machine having, in combination, stitch forming mechanism including a

curved hook needle, looper mechanism comprising an oscillatory lever, a looper lever mounted on the first lever to oscillate therewith and also arranged to oscillate independently of the first lever in a plane substantially perpendicular to the plane of oscillation of the first lever, a slide, connections between the slide and the looper lever for oscillating the looper lever, a cam roll on said slide, a closed cam engaging said roll for actuating said slide, a cam roll on the first lever, and a closed cam engaging the last cam roll for oscillating the first lever.

8. A sewing machine having, in combination, stitch forming mechanism including a curved hook needle, looper mechanism comprising a lever mounted to oscillate in a plane substantially perpendicular to the plane of the needle, a looper lever mounted on the first lever to oscillate therewith and also to oscillate independently of the first lever in a plane substantially perpendicular to the plane of oscillation of the first lever, a slide arranged to reciprocate transversely of the line of feed, a block carried by said slide and arranged to operate in a slot formed in said looper lever, means to reciprocate the slide and means to oscillate the first lever.

9. A sewing machine, having, in combination, stitch forming mechanism including a curved hook needle, looper mechanism comprising a lever mounted to oscillate in a single plane, a looper lever mounted on said first lever to oscillate therewith and also arranged to oscillate independently of the first lever in a plane angular to the plane of oscillation of the first lever, a looper carried by said looper lever, and positively acting means for oscillating said levers in timed relation to each other to carry the looper about the needle.

10. A sewing machine, having, in combination, stitch forming mechanism including a curved hook needle, looper mechanism comprising a lever mounted to oscillate in a single plane, a looper lever mounted on said first lever to oscillate therewith and also arranged to oscillate in a plane angular to the plane of oscillation of said first lever, one of said levers being arranged to oscillate in a plane substantially perpendicular to the plane of the needle, a looper carried by said looper lever, and positively acting means for oscillating said levers in timed relation to each other to carry the looper about the needle.
